GARMENT PRESS

Angus F. Hanney, Norwood, Ohio, assignor to
The American Laundry Machinery Company

Application August 5, 1933, Serial No. 683,816

7 Claims. (CL. 68—9)

This invention relates to presses, particularly of the sort used in garment and general laundry work. The specific improvement herein described relates to the positioning of the pressing members in such a press.

My invention provides an improvement in a press having coacting pressing members which have one relative movement from and into registering position and a second closing movement 10 for applying final pressure.

An object of the invention is to so arrange the coacting pressing members that only a very short stroke is necessary in the final closing movement of the press.

Another object of the invention is to provide coacting surfaces on the pressing members adapted to retain said members in registering position during the closing movement.

Other objects and advantages will appear from a consideration of the drawing and the description thereof and the essential features of the invention are summarized in the claims.

In the drawing, Fig. 1 is a side elevation of a pressing machine illustrating the use of my improved pressing members; Fig. 2 is an enlarged partial detail showing the position of the pressing members in registering position before final pressure is applied; while Fig. 3 is an enlarged sectional view along the line 3—3 of Fig. 1.

My improved arrangement of pressing members is applicable in any press having a pair of coacting pressing members wherein the members have a relative movement into registering position and closing movement in another direction.

The invention in general comprises arranging the members so that they have substantially parallel generally inclined coacting surfaces arranged to approach each other as the members move into registering position. The movement into registration may then be used to bring the pressing members into very close proximity and thereafter an actuator having a very short stroke is sufficient to cause relative movement of the pressing members toward each other for the application of final pressure.

While the invention is applicable to many types of presses, I have chosen to illustrate the use of my improved pressing members on a press of the general type illustrated, described and claimed in the copending application of John P. Singiser, Ser. No. 683,322, filed August 2, 1933. For a complete description of this machine reference may be had to the said application, only sufficient explanation being given here to permit an under-

standing of the general operation of the press described.

The press illustrated in Fig. 1 comprises a frame supported at a suitable distance above the floor and having a table 10 and arms 11 which support a head 12 rigidly secured to the frame and a bed 13 adapted to coact with the head and movable from and into registering position therewith. The arrangement disclosed for providing this registering movement comprises a bed-supporting carriage 14 supplied with rollers 15 adapted to travel on rails 16 which are supported on the table. The bed has a stem 25 extending downwardly through a bearing in the carriage, which permits vertical movement of the bed relative to the carriage. Any desired arrangement might be used for causing the relative movements necessary to bring the pressing members into registration and to apply the final pressure. For instance the bed might be moved into registering position manually and thereafter be raised into the final pressing position against the head by means of a foot treadle, or various power means might be arranged to cause these movements. In the press illustrated, the movement of the bed into registering position is provided by fluid motor 17 whose piston rod 18 is connected to the bed by link 19, cranks 20 and 21 pivoting about shaft 22 and link 23. Final pressure is applied to the pressing members 30 though a second fluid motor 24 provided with a piston, not shown, adapted to have a substantially vertical movement and provided with a piston rod adapted to extend through an opening in table 10 to coact with the stem 25 of the carriage, thus raising the bed from the carriage. A double acting snubber 26 is connected by suitable linkage to the shaft 22 for cushioning the moving parts at the ends of their inward and outward travel. Upon release of the pressure in motor 24, the bed with its associated parts moves downward due to the weight of the parts. Release of motor 17 permits spring 31, through suitable connections, to move the bed to its forward or open position.

The control of fluid power to the motors 17 and 24 is illustrated, described and claimed in my copending application, Ser. No. 683,815, filed August 5, 1933, and it will suffice here to say that the fluid pressure is supplied through conduit 27 to valve block 28 in which are located suitable valves for controlling the various motors. The valves lie in a horizontal plane with their stems in line and adapted to be actuated by cams rotating about cam-shaft 30 and con-

nected by operating rods or levers to various parts of the press. Referring to Fig. 3, fluid pressure enters through conduit 27 to a suitable passageway 51 which leads to various inlet ports 52. The valves controlling these ports are opened by cams on shaft 50, admitting fluid pressure to exhaust ports and conduits as follows: 53 controlled by valve 17a leads to fluid motor 17, 54 controlled by valve 55a leads to release cylinder 55, 56 controlled by valve 24a leads to fluid motor 24. The exhaust from motor 17 passes through conduit 53, diagonal passageway 57, port 58 controlled by valve 17b, and outlet 59. The exhaust from motor 24 passes through conduit 15 56, diagonal passageway 60, port 61 controlled by valve 24b, and outlet 62.

The connections to various parts of the press for operating the valves is as follows: The inlet and outlet valves for motor 17 are controlled by cams 63 and 64 respectively, which are pinned to shaft 50 and actuated through rod 65 and control handle 29. The inlet and outlet valves for motor 24 are controlled by cams 66 and 67 respectively, which are mounted on a sleeve shaft 25 68 freely rotatable about shaft 50 and actuated by interlock means 30, which, when the pressing members reach registering position, enters a suitable cam 31 on the bed supporting carriage. The interlock is connected by link 32, bell-crank 33, 30 and link 34 to sleeve shaft 68. The control valves for either or both motors 17 and 24 are reversed to open the press by release cylinder 55 mounted below shaft 50. This cylinder has a piston provided with a shoe suitable for engaging flanged 35 collars 69 and 70 on cam shaft 50 and sleeve shaft 68 respectively, whereby these shafts are returned to a position where valves 17a and 24a are closed and valves 17b and 24b are opened, thus relieving the pressure in motors 17 and 24. 40 The control valve 55a for release cylinder 55 is actuated by cam 71, which is freely rotatable about shaft 50 by rod 72 connected with a finger guard 36. This guard depends in a freely swingable manner before the head in position to be 45 struck by the operator's hands if they are accidentally resting upon the buck as it moves toward registering position. Movement of the guard 36 in a clockwise direction, either accidentally, as just mentioned, or in the regular 50 opening of the press after completion of the pressing operation, admits fluid pressure to release cylinder 55 with consequent opening of the press.

55 My invention comprises the arrangement of the coacting pressing members so that their movement into registering position brings their coacting surfaces into such close proximity that a very short movement toward each other surfaces to apply final heavy pressure. As shown 60 in the drawing, head 12 and bed 13 are provided with substantially parallel and generally inclined surfaces sloping downwardly away from the operator and arranged in such a manner that when the parts reach registering position, as shown 65 in Fig. 2, but a very slight movement in vertical direction is necessary to press the members together.

70 These inclined surfaces may be substantially flat or they may have various arcuate forms and preferably I so arrange the surfaces that portions thereof serve to retain the members in registering position during the closing movement of the press. That is to say, there would be a tendency for a pair of flat inclined surfaces

to slip one upon the other when the bed moved into engagement with the head. As more clearly shown in Fig. 2, portions 38 and 39 near the forward edge of the press members are arranged in such a manner as to prevent slippage between the members during the final closing movement. The arrangement shown comprises a substantially horizontal portion along the line 40 which is a tangent to the arc of the bed surface at that point. I find that having a portion of the 10 coacting surfaces thus arranged horizontally prevents relative slippage between the members, but it is obvious that the surfaces might be further curved toward the forward edge so as to incline slightly in the opposite direction from the 15 general incline of the rest of the surface and thus enhance the retaining action between these portions of the pressing members.

Many advantages accrue from this arrangement of the pressing members, the most obvious 20 of which is apparent from an inspection of Fig. 2 where but a slight movement of motor 24 will suffice to apply the final pressure and this results in a great saving in fluid pressure, inasmuch as the final pressure cylinder usually has a large 25 area and high fluid consumption per inch of travel.

Another advantage of the inclined bed arrangement is that it gives a greater clearance 30 between the rear side of the bed and the front edge of the head as the bed passes thereunder, as shown by the dash-dot position of the bed at 41 in Fig. 1 and therefore, the arrangement 35 will accommodate garments of varied thickness without disturbing the lay of the work. For instance, in pressing double cuffs, the parts of the garment do not always lie flat against the bed and many times arch upwardly so as to contact the head when the bed moves into registering 40 position, if the usual horizontally arranged bed is used. As my improved pressing members move toward each other such upstanding portions of the work are pressed down into position without disturbing the lay.

Another advantage is that the finger guard may 45 be mounted in a lower position than usual and still not interfere with the garment on the bed. Thus the guard more efficiently performs its functions because less distance is permitted for the operator's hands to pass under the head as the parts move into registration. The position 50 of the parts in Fig. 1 shows that the guard practically sweeps the last edge of the bed as it passes thereunder.

55 Still another advantage is that there is less likelihood of disturbing the lay of the work, due to the very short distance travelled in applying the final pressure.

What I claim is:—

60 1. In a press of the class described, a pair of cooperative pressing members having a relative movement into registering position and a closing movement in a direction substantially normal to said registering movement, and said members having substantially parallel surfaces generally inclined relative to the direction of registering movement and arranged to approach each other as the members move into registering position.

65 2. In a press of the class described, a pair of cooperative pressing members having a relative movement into registering position and a closing movement in another direction, and said members having substantially parallel generally inclined surfaces arranged to approach each other as the 70 75

members move into registering position, portions of said surfaces being arranged to retain said members in registering position during the closing movement.

5 3. In a press of the class described, a pair of cooperative pressing members having a relative movement into registering position and a closing movement in another direction, said members having substantially parallel generally inclined surfaces arranged to approach each other as the members move into registering position, and portions of said surfaces lying in a plane substantially normal to the direction of closing.

10 4. In a press of the class described, a pair of cooperative pressing members having a relative movement into registering position and a closing movement in another direction, said members having substantially parallel generally inclined surfaces arranged to approach each other as the members move into registering position, and an actuator having a short stroke for causing said closing movement.

15 5. In a press of the class described, a pair of cooperative pressing members having a relative movement in a substantially horizontal direction into registering position and a closing movement in a substantially vertical direction, said members having substantially parallel generally inclined surfaces arranged to approach each other as the members move into registering position, means for causing the registering movement, and power

means having a short stroke for causing said closing movement.

20 6. In a press of the class described, upper and lower coacting pressing members having a relative movement into registering position, said members having substantially parallel generally inclined surfaces arranged to approach each other as the members move into registering position, power means for moving one of said members, control means therefor, a finger guard depending before the upper member and closely adjacent the path of travel of the upper portion of the inclined surface of the lower member, and an operative connection between said finger guard and control means, whereby movement of the guard in the direction of registering movement actuates the control means in a direction to effect out-of-registration relative movement of said pressing members.

25 7. In a press of the class described, a pair of cooperative pressing members having a relative movement into registering position and a closing movement in another direction, and said members having substantially parallel generally inclined surfaces arranged to approach each other as the members move into registering position, the pressing members having provisions for retaining said members in registering position during the closing movement.
